UNITED STATES PATENT OFFICE.

HORACE H. TEETER, OF CARBONDALE, ILLINOIS.

CHURN.

SPECIFICATION forming part of Letters Patent No. 327,620, dated October 6, 1885.

Application filed May 17, 1884. Serial No. 131,803. (No model.)

To all whom it may concern:

Be it known that I, HORACE H. TEETER, a citizen of the United States, and a resident of Carbondale, in the county of Jackson and State 5 of Illinois, have invented certain Improvements in Dashers for Churns and other like Machines, of which the following is a specification.

My invention relates to the peculiar construction of the wire dasher or beater of a churn or other like machine; and it consists in forming the wings or paddles of the beater of overlapping volutes or spirals of wire, the entire set of wings being preferably and usually made from one piece of wire. In order to prevent the wire from rusting, I usually make the dasher or beater and then tin the wire in a well-known way, whereby every part of the wire will be coated with a non- 20 oxidizable covering of the tin.

In the drawings I have shown my improved dasher or beater as applied to a churn, the dasher being mounted rotatively on the cover of the churn.

25 In the said drawings, Figure 1 is a vertical mid-section of a churn provided with my improvements, the dasher or beater itself being in elevation. Fig. 2 is a horizontal or transverse section of my improved dasher or beater.

Let A represent a churn—say of some ceramic material—provided with a wooden cover, B, which is held firmly in place by screw-rods *a*, which connect said cover with 35 a wooden base, C, and which have suitable nuts *b*.

D is a metal bed-plate, secured on the cover B, and provided with standards *c c'*, in which are rotatively mounted a shaft, E, provided 40 with a crank, F. On shaft E is fixed a bevel gear-wheel, G, which meshes with a bevel-pinion, H, fixed on the upper end of the dasher or beater stock I. This pinion H has a long boss which provides the vertical dasher- 45 stock with a rotative bearing in the bed-plate D; and in order to provide a still better bearing for the stock its upper end may have, as shown, a second bearing in a projection, *d*, on the upright *c'*.

50 Rotation of the crank imparts a rapid ro-

tary motion to the dasher-stock. The dasher is wholly suspended from the cover, and may be fitted to any ordinary churn, the bearing usually employed for the foot of the dasher-stock being omitted.

J J represent the wire wings of the dasher or beater. There may be any desired number of these, but I have shown four in the drawings. These wings are composed of overlapping volutes or spirals of wire, and 6c are formed by first boring small holes in the dasher-stock at suitable intervals or distances apart, and at right angles, where four wings are employed, and then drawing the wire through these holes. In inserting the wire 65 I usually form one spiral or volute, half of which appears on each side of the stock, then pass the wire through the proper hole at right angles to the spiral already formed and form a second spiral at right angles to 70 the first. Then I proceed to form a spiral which overlaps the first, and next a spiral which overlaps the second, proceeding in this manner until all the spirals are formed with one piece of wire. This is advantageous 75 where iron wire is employed, as will usually be the case, as the wire is most apt to rust at the ends.

Such a dasher-wing is easily and cheaply constructed, and by the overlapping of the 8c spirals, as described, the wings are strengthened and a suitable reticulated surface is formed that is well adapted to churning and beaters of all kinds. These reticulated wings have their meshes finest and with most acute 85 crossing angles near the outer edges and in the middle portion, where their action is most effective. I am not aware of any other construction which produces so good results in so simple a way.

90 My improved dasher is well adapted to all machines where liquids are to be whipped or beaten up.

I do not broadly claim a dasher made from wire, as these have been before proposed for 95 churning, egg-beaters, and similar machines; but what I do claim is—

An improved dasher or beater for churning and other similar machines, constructed with a stock, I, having perforations through it at 100

suitable distances apart, as described, and with wings J J, formed of wire passed through the holes in the stock, each wing being formed in volutes having different centers, and the wires of one crossing the wires of the other volute, substantially as herein specified.

In witness whereof I have hereunto signed my name in the presence of two subscribing witnesses.

H. H. TEETER.
